UNITED STATES PATENT OFFICE.

CHARLES W. JENKS, OF CHICAGO, ILLINOIS.

GAS OR OIL HEATING-STOVE.

SPECIFICATION forming part of Letters Patent No. 428,104, dated May 20, 1890.

Application filed October 28, 1889. Serial No. 328,430. (No model.)

To all whom it may concern:

Be it known that I, CHARLES W. JENKS, of Chicago, in the State of Illinois, have invented certain new and useful Improvements in Gas or Oil Heating-Stoves, of which the following is a specification.

My invention relates to gas or oil stoves for warming apartments; and the object of my improvements is to provide means for retarding the products of combustion in a continuously-ascending course in a combustion-chamber in conjunction with an air-heating flue surrounding the combustion-chamber, whereby a current of air created by the heat of combustion is drawn rapidly through such heating-flue, heated therein, and discharged at the top of the stove. I also provide an exterior air-flue surrounding the air-heating flue, and obstructed at the top for preventing radiation and increasing the draft in the air-heating flue. The warming is thus produced chiefly by an increased circulation of warm air, instead of by radiation, as heretofore done with heating-stoves. I have attained this object in the stove constructed as illustrated in the accompanying drawings, in which—

Figure 1 is a side elevation of such stove. Fig. 2 is a central vertical section showing the interior construction and arrangement. Fig. 3 is a horizontal section on the line 3 3 of Fig. 2. Fig. 4 is a horizontal section of the combustion-chamber enlarged on the line 4 4 of Fig. 2.

The base of the stove is preferably made of four concentric rings *a*, connected together by radial connections *a'*, all the space between the rings and connections being open. The burners *a²* are supported on the inner ring. On the next ring is a sheet-iron inner casing *b*, preferably cylindrical in form, the lower edge being fitted in a rabbet in said ring, as shown in Fig. 2. This casing constitutes the combustion-chamber.

From seven to ten inches from the burners there are attached three or more brackets *c*, and upon these is rested a series of plates *c'*, which plates are connected together by bolt-rods *c²*, there being short sections of tubing *c³* interposed to keep the plates apart. Every alternate plate is continuous and of smaller diameter than said casing, so as to leave a narrow way *d* all around between the casing

and the periphery of the plate, and the other plates are of the same diameter as the casing, so as to fit tightly therein, and are provided with openings *d'* in the center. The products of combustion are retarded by these plates and take a zigzag upward course around and through them, as indicated by the arrows within said casing, being deflected against the casing as they pass the periphery of the continuous plates at *d*. The top of said inner casing is covered by a cap *e*, having a flange *e'*, which fits tightly over the same, and has a flanged opening *e²*, with which the smoke-pipe *e³* is connected for carrying off the smoke and fumes of combustion. On the next ring is a similar casing *b'*, which surrounds said inner casing *b*, and the space inclosed between said two casings forms the air-heating flue, which is open at the top and bottom, and on the outer ring is another similar casing *b²*, which is open at the bottom, but closed at the top by a plate *f*, with a large opening in the center, having a downwardly-projecting flange *f'*, which extends down to or slightly below the level of the cap *e*. The space inclosed between said casings *b'* and *b²* constitutes the exterior air-flue.

The cap *e* is provided with an extension beyond the flange *e'*, which reaches nearly to the lower end of the flange *f'*, leaving only a narrow passage-way all round at *f²* between said extension and said last-named flange. To the outer edge of said extension is attached a flange *e⁴*, and there is a row of perforations *e⁵* in said extension between the flanges *e'* and *e⁴*. Said flange *e⁴* divides the upper portion of the air-heating flue, so that the air in said flue nearest to the inner casing *b*, and consequently the hottest, will pass within said flange, and be thereby forced to pass through the openings *e⁵*, which afford a more restricted passage-way than that at *f²*. This portion of the air is thereby retarded and further heated on its way between said inner casing and the flange *e⁴*. The air in the exterior flue intercepts the radiation from the exterior of the air-heating flue, and as it is warmed thereby it will rise and pass over the top of the casing *b'*, and will thence be drawn down through the contracted passage-way at *f³* between the upper part of said casing and the flange *f'*, and thence down and out through the passage-

way at f^2 . The flange f' , it will be seen, forms a chamber or enlarged flue directly over the combustion-chamber. Said enlarged flue is open at the top, and all of the heated currents of air are emptied into the same at the bottom and discharged therefrom at the top into the room.

The top of the stove is covered with an ornamental piece g , provided with a reticulated top plate g' for allowing the currents of hot air to pass out from said enlarged flue.

Doors h are provided in the casings b , b' , and b^2 for lighting the fire, the inner ones being made to slide up, as the space is hardly sufficient for a hinged door.

The pipe h' for supplying the fuel is shown in Figs. 2 and 3.

Among the advantages which the stove thus constructed possesses over others of the class to which it relates are the more direct draft for the smoke and fumes of combustion, the saving of heat in greater proportion, it being to a much greater extent than heretofore prevented from passing off through the smoke-flue, and the preventing of radiation from the sides to such an extent that the stove can be placed in closer quarters or near an article of furniture without liability to injure the same.

What is claimed is—

1. The stove constructed substantially as shown and described, having the combustion-chamber in the center provided with deflecting-plates constructed as shown, and arranged over the burners and under the smoke-flue,

the air-heating flue surrounding the combustion-chamber, an exterior air-flue surrounding the air-heating flue, and an enlarged chamber or flue placed directly over the combustion-chamber and communicating with the air-heating flue and exterior air-flue by passages e^5 , f^2 , and f^3 , as specified.

2. The stove constructed as shown and described, having the central combustion-chamber provided with deflecting-plates over the burners, the air-heating flue surrounding the combustion-chamber, the cap e , having flanges e' , e^2 , and e^4 , and perforations e^5 , in combination with the casing b^2 , provided with the top plate f , having flange f' , arranged, as shown, relatively to the cap e , as specified.

3. In a gas or oil heating-stove, and in combination, a central combustion-chamber having the burners near the bottom and the smoke-flue connected at the top, deflecting-plates c' , arranged over the burners and below the smoke-flue, a flange e^4 , connected to an extension of the top plate of the combustion-chamber provided with a row of perforations e^5 , the casing b' , surrounding the combustion-chamber and extending above it, the casing b^2 , surrounding casing b' and extending above it, and the plate f , provided with the flange f' , said plate and flange being arranged, as shown, relatively to casing b' .

CHARLES W. JENKS.
